LESTER C. BLACK, OF LOS ANGELES, CALIFORNIA.

ROTARY DISK DRILL BIT.

Application filed January 8, 1925. Serial No. 1,199.

The invention relates to a rotary drilling bit in which a plurality of rotating cutting disks are employed to cut the formation.

Drill bits of this general type have been very widely used in the drilling of oil wells. These prior drill bits have invariably comprised a body, a plurality of disks and means for mounting the disks on the body. The disks have usually been mounted on the body by means of a separate pin or stud, which formed an axle on which the disk was journaled. Due to the fact that these pins or studs are separate or detachable, means have been provided for attaching them to the body, this means in some types comprising a thread on the pin, which is screwed into engagement with a thread in the body of the bit, with a lock nut on the end of the inserted pin. Other types use a pin that is inserted through a hole provided in the body and use a combination of screwed bushings and lock nuts to hold the disk in place. Bearings of this type possess an inherent weakness and must be comparatively small. The pins carry the entire weight applied on the tool when drilling and, due to the relatively small size of the pins, the pins have not withstood the load. The size of the pin is limited, due to various mechanical limits imposed on the design of the various bits and by the necessity of maintaining the disks in proper position and in proper relation to each other. The pin, therefore, constituted the weakest part of the drill.

In accordance with my invention, I provide a disk bit of such construction that the objectionable features heretofore mentioned are eliminated. An object of my invention therefore is to provide a rugged and substantial bearing for the disk.

Another object of the invention is to provide means for holding the disks on the load carrying bearings so that they will not become displaced in use.

A further object of the invention, is to position the load carrying bearing so that it presents its greatest strength in the direction of the reaction caused by the operation of the disk against the formation.

The invention possesses other advantageous features, some of which with the foregoing will be set forth at length in the following description, where I shall outline in

full that form of my invention which I have selected for illustration in the drawings accompanying and forming part of the present specification. In said drawings I have shown one form of drill bit embodying my invention, but it is to be understood that I do not limit myself to such form, since the invention as set forth in the claims, may be embodied in a plurality of forms.

Referring to said drawings:

Figure 1 is a side elevation of the lower portion of a drill bit embodying my invention.

Figure 2 is a compound section of the drill bit shown in Figure 1, Figure 2^a being a section taken on the line 2^a—2^a Figure 1, and Figure 2^b being a section taken on the line 2^b—2^b, Figure 1.

Figure 3 is an underneath view of the drill bit of my invention.

Figure 4 is an elevation of one cutting disk and its bearing, part thereof being omitted to better show the construction.

Figure 5 is a cross section taken on the line 5—5, Figure 4.

Figure 6 is an elevation of the filler block forming part of the device of my invention.

Figure 7 is an underneath view of the filler block.

Figure 8 is a vertical section of the filler block taken on the line 8—8 Figure 6.

Figure 9 is a side elevation of the lower portion of the drill body.

Figure 10 is an end elevation of the lower portion of the drill body.

The drill bit of my invention comprises a body 12, preferably formed of steel, the lower portion of which is preferably tapered to provide two substantially flat, inclined sides 13 and 14. Formed on each side of the body and integral therewith is a projection which constitutes the load carrying bearing for the applied cutting disk. The projection 15 is formed on one side of the body and the projection 16 is formed on the other side of the body. The axes of these projections are perpendicular to the faces 13 and 14 and consequently are inclined to the vertical axis of the body. The two projections are oppositely offset with respect to the vertical axis of the body as shown in Figure 9, so that one projection 15 lies to the left of the vertical axis and the

other projection 16 lies to the right of the vertical axis. Each projection is formed on its lower surface with an arcuate surface 17, which is formed substantially on a curve 5 concentric to the curve of the bore of the applied disk, and includes a bushing 19 forming a bearing surface of substantially the same curvature as the bore of the applied disk. These surfaces are so disposed 10 that the line of reaction of the cutting disk, during the operation of the tool bisects the arcuate surface. In other words, the arcuate surface is presented to the load, so that, in the operation of the drill, substantially the 15 entire load falls on the arcuate surface. These surfaces are offset oppositely with respect to the vertical axis of the body, so that the bisectors of the two arcs intersect, as shown in Figure 9. The broken lines 20 A—B, which bisect the two arcuate surfaces, also represent the line of force due to the reaction of the cutting tool. The upper surface of each projection is preferably arcuate and concentric with a point on 25 the bisector below the point of concentricity of the arcuate surface 17, so that the maximum diameter of the projection is less than twice the radius of the arcuate surface 17. Therefore each projection has 30 major and minor dimensions, measured in a plane parallel to one of the sides 13 and 14.

Each projection is provided on its lower edge, substantially coextensive with the arcuate surface 17, with a flange 18, which 35 serves to hold the applied disk in position on the projection bearing. The radius of the arcuate surface 17 is preferably less than the radius of the bore of the applied disk 40 and the bushing 19 is interposed between the surface 17 and the bore, to take the wear. The bushing extends beyond the ends of the arcuate surface and is held 45 against rotation by an applied block, as will hereinafter be set forth.

Journalled on each projection is a cutting disk, the cutting disk 21 being journalled on the projection 15 and the cutting disk 22 being journalled on the projection 16. 50 These cutting disks may be made in any desired design and are axially rotatable on their respective bearings during the operation of the drill.

The projection is of smaller size than the bore in the disk and a filler block is employed to hold the bore in contact with the arcuate surface 17 and to properly position the disk on the load carrying bearing 15. Interposed between the upper side of 55 the projection and the adjacent surface of the bore of the disk is a filler block 23 having an inner surface 24 which is concentric with and which forms a snug fit with the upper surface 25 of the projection. The 60 filler block 23 fits into the space in the

bore of the disk between the surface of the bore and the projection 15 and is provided on its upper side with an arcuate surface 26, which, when the block is in position, is concentric with the arcuate surface 17 and 70 the bearing surface of bushing 19. The filler block is provided along its upper side with an overhanging flange 27 which, when the block is in position, overlies the cutting disk and holds it in position. At its edges, 75 the filler block is provided with shoulders 28 against which the ends of the bushing 19 abut, thus holding the bushing in position against rotation. During the operation of the drill, substantially the entire drilling 80 load is carried by the projections 15 and 16, the filler block serving principally to form guide bearings for the rotating disk. Interposed between the rotating disk and the body of the drill is a washer 29, which is 85 held against rotation by a stud 31 seated in the body, so that the wear produced by the rotation of the disk falls on the washer.

By virtue of the opposite offset positions of the projections 15 and 16 and the opposite 90 inclinations of the bisectors of the arcuate surfaces 17, the filler blocks 23 on opposite sides of the body are in partial alinement and means extending through the alined or overlapping portions is employed for firmly 95 holding the filler blocks in position. The body 12 is formed with a transverse aperture 33, the extension of the aperture beyond the body lying partially in the projections 15 and 16 as shown in Figures 9 and 10. Each 100 projection is provided in its upper surface with an arcuate groove 34, which comprises an extension of the surface of the aperture in the body. Each filler block 23 is provided with an arcuate groove 35 therein, which is 105 a conjugate of the groove 34 formed in the projection, so that when the filler block is fitted into position, a continuous hole is formed through the filler block and body. The grooves in the projections and in the 110 filler blocks on opposite sides of the body, are alined with each other and with the hole through the body, forming a straight bore transversely through the body. The filler blocks are held in position by a bolt 36 extending through the body and the filler block and being tightly secured therein. The filler blocks and the projections are provided, 115 around the grooves therein, with seats 37 and 38, inclined to the surfaces of the filler blocks and the projections, and parallel to the vertical axis of the body. The surfaces of these seats are perpendicular to the axis of the bolt 36 and are engaged by the 120 surfaces of the head and nut on the bolt. By virtue of this construction very rugged bearing for the cutting disk is provided, so that the drill may be used to its maximum capacity. Rotation of the cutting disk in either direction will not tend to loosen the 125

bearing for the disk and the disk may be readily dismounted and replaced when worn.

Means are provided for supplying a fluid vehicle or lubricant to the cutting edges of the disks, and in the present instance this means comprises the conduits 39 extending downward through the body and opening at the bottom of the body at the holes 41. Mud or other vehicular or lubricating fluid is discharged downward through the conduits 39 into the bottom of the hole being drilled.

I claim:

1. In a rotary disk drill bit, a body, an integral projection on the body, said projection having an integral flange, a cutting disk operatively disposed behind said flange and journalled on the projection, and means for removably retaining said disk in operative position.
2. In a rotary disk drill bit, a body, an integral lateral projection on the body having a lower bearing face of substantially the same curvature as the bore of an applied cutting disk, a flange on said projection substantially coextensive with said bearing face, a cutting disk mounted on the projection and disposed behind the flange and bearing against said lower face, and means for removably retaining said disk on said projection.
3. In a rotary disk drill bit, a body, a lateral projection on the body of lesser size than the bore of an applied cutting disk, one face of the projection being of substantially the same curvature as the bore in the disk, a flange on said projection a cutting disk mounted on said projection and engaging said face and a removable block filling the space between the projection and the surface of the bore in the cutting disk, whereby said disk may be removed from the projection upon removal of said block.
4. In a rotary disk drill bit, a body, a lateral integral projection on the body, the axis of the projection being inclined to the axis of rotation of the body, a flange on only the lower side of the projection, a cutting disk disposed on the projection and disposed behind said flange, and means for removably retaining said disk upon said projection.
5. In a rotary disk drill bit, a body and a bearing for an applied cutting disk comprising a load carrying bearing projecting from the body and adapted to engage an arc of the bore of the disk on the lower side thereof, a flange secured to said load carrying bearing and a disk centering bearing secured to the body and adapted to engage an arc of the bore of the disk on the upper side thereof, said disk centering bearing being removable from said load centering bearing to permit the disk to be shifted from its centered position for removal from the load carrying bearing.
6. In a rotary disk drill bit, a body, a pro-

jection on the side of the body having a bearing surface on its under side, a flange overlying said bearing surface, a cutting disk engaging said bearing surface and underlying said flange, a block cooperating with said projection and having a bearing surface on its upper side in bearing engagement with the disk and a flange on the block overlying the disk.

7. In a rotary disk drill bit, a body, integral projections on opposite sides of the body, said projections being oppositely offset with respect to the vertical axis of the body, a block associated with each projection, a bolt securing said blocks to the body and a cutting disc journalled on each projection and block assembly.

8. In a rotary disk drill bit, a body, projections on opposite sides of the body, said projections being oppositely offset with respect to the vertical axis of the body, an arcuate surface on the lower side of each projection, a block associated with each projection, unitary means for detachably holding the two blocks in position, an arcuate surface on the upper side of each block, the arcuate surfaces of each projection and block assembly being concentric and a cutting disk journalled on each projection and block assembly, whereby said disks may be removed from said projections upon removal of said blocks.

9. In a rotary disk drill bit, a body, an integral projection on each side of the body, said projections forming load carrying bearings for applied cutting disks and means including blocks associated with the projections for centering each of said disks on an axis offset from the center of its corresponding projection.

10. In a rotary disk drill bit, a body, integral projections on opposite sides of the body, the projections being oppositely offset with respect to the vertical axis of the body, an arcuate bearing surface on the lower side of each projection, the bisectors of said arcs being inclined rearwardly with respect to the respective tangents of the paths of movement of said projections, a removable block cooperating with each projection, each block having an arcuate upper surface concentric with said arcuate surfaces on the projections, a projection and its cooperating block forming a bearing for an applied cutting disk, said disks being removable from said projections upon removal of said blocks.

11. In a device of the class described comprising, a body, a cutting disk having a circular bore, and a bearing for this disk comprising a projection extending from said body and engaging an arc of the bore of the disk, said arc being less than one-half of the circumference of the bore, and a flanged block cooperating with the projection and

- engaging another arc of the bore of the disk, 5 said block serving to retain the disk upon the projection and being removable to permit removal of said disk from said projection.
12. In a rotary disk drill bit, a body, a projection extending from one face of said body, said projection having major and minor dimensions measured in a plane parallel to said face, an arcuate bearing surface on one side of said projection, a cutting disk having a circular bore positioned on said projection and bearing on said arcuate surface, and means for retaining said cutting disk in position on said projection, said means including a block for supplementing said minor dimension.
13. In a device of the class described comprising, a body having a side face, a projection secured to said body and extending outwardly from said face, said projection having major and minor dimensions measured in a plane parallel to the general plane of said face, a cutting disk having a circular bore and adapted to be disposed upon said projection, and means detachably secured in position adjacent said projection for supplementing said minor dimension to form a circular bearing for said disk and for retaining said disk in position on said projection.
14. In a device of the class described comprising, a body member having a side face, a cutting disk adapted to be secured adjacent said face and having a circular bore, a projection fixed to said body and extending outwardly from said face, a flange carried by said projection on the outer end thereof, the dimensions of said projection and flange being such that said disk may be positioned on said projection or removed therefrom, and another flange detachably secured to said projection for retaining said disk in position on said projection.
15. In a device of the class described comprising, a body adapted to be rotated, a projection extending from said body, a cutting disk positioned on said projection, two arcuate bushings fixed to said projection and forming bearing surfaces for said disk, said bushings being positioned so as to be substantially bisected by a line inclined rearwardly with respect to the tangent of the path of movement of said projection.

In testimony whereof, I have hereunto set my hand.

LESTER C. BLACK.
